UNITED STATES PATENT OFFICE.

WILLIAM C. MACFADDEN, OF FARGO, NORTH DAKOTA.

SAFE.

Application filed August 29, 1924. Serial No. 734,929.

To all whom it may concern:

Be it known that I, WILLIAM C. MACFADDEN, a citizen of the United States, residing at Fargo, in the county of Cass and State of North Dakota, have invented new and useful Improvements in Safes, of which the following is a specification.

The almost daily occurrence of robberies of small banks, and particularly country banks, has led to a wide spread study of the problem of constructing a safe which is impregnable to modern methods of attack. It is well known that all metals suitable for making safes can be burnt by gas or electric torches, although safes which are proof against blasting have been constructed of manganese steel. Such safes are in present, general use.

As far as applicant is aware, in all of the successful robberies of these manganese steel safes, the procedure has been about as follows. A small hole is first burnt or drilled at or near the top of the safe to permit filling the safe with water. After filling with water, a hole large enough to permit the withdrawal of the contents is burnt in the top of the safe. During the burning, the water prevents the intense heat of the torch from consuming or melting the valuable contents of the safe.

It is my object to guard against robberies of the kind described above by providing a receptacle for valuables formed to efficiently resist attack and adapted to be so placed in any of the modern safes that it is inaccessible and cannot, therefore, be reached for burning.

A further object is to provide an inexpensive device of this kind having a series of protected compartments which are easily accessible when the safe door is open.

This invention also includes certain other novel features of construction which will be more fully described and pointed out in the following specification and claims.

In the accompanying drawings, which illustrate the best form of my device at present known to me, Figure 1 is a front elevation of the protected receptacle removed from the safe proper; Fig. 2 is a side elevation of the same in position in a modern safe, the safe being shown in central, vertical section; Fig. 3 is a plan view of the device within the safe, which is shown in central, horizontal section and Fig. 4 is a front elevation of the safe with the door closed.

The guarded compartment or receptacle A is substantially rectangular and is provided with a strong, outer casing 5 extending about the top, bottom and lateral sides. 60 The front of the receptacle A is open so as to allow ready access to a series of pigeon holes formed by horizontal partitions 6 and vertical partitions 7. To further protect the sides and top of the receptacle A, a layer 8 of concrete is placed between the casing 5 and the inner wall 9. The back 10 of the receptacle A may be open or closed, as desired, although in the structure shown, the back is open. 70

The protected receptacle A may be inserted through the opening for a circular door 11 in a manganese steel safe 12. When in place, the receptacle occupies the lower part of the safe and extends from the back wall 13 thereof to the inner surface of the door. Thus, tilting of the receptacle is prevented either in a forward or backward direction. Suitable lugs 15 fast on the sides of the receptacle are adapted to receive bolts 14 for securing the same upon the back wall 13 of the safe. 80

When in place in the safe, it will be observed that the receptacle A is spaced a substantial distance away from both the top and the lateral walls thereof. In use, the most valuable property to be stored (such as gold, negotiable bonds and currency of the higher denominations) is placed within the receptacle A, the non-negotiable securities, silver and less valuable papers being stored elsewhere in the safe. 85

If it be attempted to rob the safe by the method above described, the contents of the receptacle A will be inaccessible even after the outer wall of the safe has been penetrated. To reach the receptacle A with the torch, it would require not only that a substantial part of the water be removed from the safe but that a very large hole be cut in the top to permit the torch to be manipulated within the safe body. Under these conditions, the concrete layer 8, makes it extremely difficult, if not impossible, to rapidly burn a hole in the receptacle A. Further, the time required to burn a large enough hole in the top of the safe to permit the necessary manipulation of the torch in contact with the casing 5 is so excessive that no such method of attack would be practical. 100 105 110

As an alternate method of securing the receptacle A within the safe, the back and

bottom of the receptacle may be cemented to the back and bottom of the safe, the space beneath the receptacle being filled with the cement. With such an arrangement, the casing 5 would be extended over the back of the receptacle and the bolts 14 and lugs 15 could be omitted.

The casing 5 is made of a rigid, tough metal which is reinforced by the grid formed 10 by the horizontal and vertical partitions 6 and 7. Thus, the device is rendered sufficiently strong to prevent destruction by such pounding or crushing forces as would be exerted through a hole in the safe. It will be 15 noted that the pigeon holes are open to the front so that the contents of the receptacle A are readily accessible when the door 11 of the safe is open.

Having described my invention what I 20 claim as new and desire to protect by Letters Patent is:

1. In a device of the class described the combination with a safe having a door, of a receptacle to be guarded adapted to be 25 inserted through said door, said receptacle being disposed in spaced relation with the top of the safe, and a protective casing on the top of said receptacle, the front thereof being open to allow access to the contents 30 through said door.

2. In a device of the class described the combination with a safe having a substantially vertical back wall and a door opposite said wall, of a substantially rectangular receptacle to be guarded adapted to be inserted through said door into engagement with said back wall, said receptacle being disposed in spaced relation with the top and lateral sides of the safe, and a protective casing on the sides and top of said receptacle. 35

3. In a device of the class described the combination with a safe having a substantially vertical back wall and a door opposite said wall, of a receptacle to be guarded adapted to be inserted through said door into engagement with said back wall, said receptacle being disposed in spaced relation with the top and lateral sides of the safe 40 and extending from the back wall to the door thereof, a protective casing on the sides and top of said receptacle, and horizontal and vertical partitions forming pigeon holes accessible from the front of said receptacle and constituting a reinforcing grid 45 within the same. 50

In testimony whereof, I have hereunto signed my name to this specification.

WILLIAM C. MACFADDEN.
